OSCAR H. GRAVELINE, OF MERIDEN, CONNECTICUT.

MUSICAL TOY.

1,258,558.

Specification of Letters Patent.

Patented Mar. 5, 1918.

Application filed July 18, 1917. Serial No. 181,391.

To all whom it may concern:

Be it known that I, OSCAR H. GRAVELINE, a citizen of the United States, residing at Meriden, in the county of New Haven and State of Connecticut, have invented new and useful Improvements in Musical Toys, of which the following is a specification.

This invention comprehends the provision of a musical toy, particularly designed to 10 create a sound similar to a snare drum, but susceptible of creating various noises for the amusement of children, the invention aiming to provide a toy of this character which can be most conveniently handled and manipulated, and also manufactured and sold at a 15 nominal cost.

The nature and advantages of the invention will be better understood when the 20 following detail description is read in connection with the accompanying drawing, the invention residing in the construction, combination and arrangement of parts as claimed.

In the drawing forming part of this specification like numerals of reference indicate 25 similar parts in the several views and wherein:—

Figure 1 is a perspective view of the preferred form of the invention.

30 Fig. 2 is a longitudinal sectional view therethrough.

Fig. 3 is a perspective view of a modified form of the invention.

Fig. 4 is a similar view of a still further 35 modified form.

Fig. 5 is a transverse sectional view taken on line 5—5 of Fig. 4.

Fig. 6 is a detail view of one of the 40 springs.

Referring to the drawing in detail and particularly to Figs. 1 and 2, the toy essentially consists of a base 10 which may be constructed from any suitable material and configuration, it being preferably 45 constructed of wood and of elongated rectangular formation in cross section. Arranged at one end of the base is what I term a sounding block, which in this instance is hollow, and preferably constructed from a single 50 blank of metal. The sounding block is substantially of U-shaped formation in cross section, including a top piece 11, front and rear walls 12 which terminate short of the base 10, and side walls 13 which are ar- 55 ranged to be secured to the opposite longitudinal edges of the base 10 in any suitable

manner, thus rigidly supporting the sounding block on the base.

Rising from the opposite longitudinal edges of the base 10 at an appropriate point 60 in its length, are spaced parallel standards 14 between which is journaled a shaft 15, preferably of rectangular formation in cross section. Secured to the upper surface of the shaft 15 is a finger actuated clapper 16, 65 which consists of a flat elongated piece of material, preferably wood. The clapper is secured at an appropriate point in its length to the shaft 15, and the latter is positioned with respect to the sounding block so that 70 the clapper normally assumes a true horizontal position, considering the position in which the toys are disclosed in the drawing. One end of the clapper overlies the sounding block while the opposite end projects a 75 short distance beyond the corresponding extremity of the base 10. Secured to the underside of the clapper adjacent that extremity which overlies the sounding block, is a round headed tack or the like 17 which 80 contacts the sounding block to create a comparatively loud noise, when the clapper is actuated.

The toy also embodies a leaf spring 18 which has one end formed to provide a hook 85 19 which embraces the edge of the base at one end thereof, and has a portion of its length normally contacting the upper surface of the base as clearly shown in Fig. 1. The spring has its opposite extremity curved 90 upwardly and rearwardly and interposed between the shaft 15 and clapper 16 being securely held in position between the fastening elements 20 outlined for securing the clapper to the shaft. This end of the spring 95 is also formed with a terminal flange 21 which bears against one of the adjacent sides of the shaft as shown. Manifestly, the disposition of the spring is such that it normally maintains the clapper in the position shown in Fig. 1, and when the clapper is actuated to move the same away from the sounding block, the spring is tensioned to forcibly return the latter to normal position, or in other words in contact with the 100 sounding block to create the desired noise.

In use the toy is held in the left hand, and resting the thumb of the right hand upon the base 10, and letting the four fingers of the right hand slip downwardly over the adjacent extremity of the clapper, one after the other, a sound is created which imitates a 110

snare drum, a roll call, and the beat of marches. The sound can be varied by moving the fingers over the clapper in the manner stated with more or less rapidity. It will be observed that the finger engaging end of the clapper is beveled or inclined as at 22 to permit the fingers to slip easily over this end, which is desirable for a convenient manipulation of the toy.

10 In Fig. 3 I have disclosed a modified form of the invention wherein the base is indicated at 23, and the sound block at 24. In this form of the invention the entire toy is preferably constructed from wood, and the sound block is solid. The toy in this form of the invention is similar in other respects to the preferred form of the invention hereinabove described, and is operated in identically the same manner and for the same purpose.

20 In Fig. 4 I disclose a still further modified form of the invention, which is also by preference constructed of wood, although other suitable material may be employed in its production. In contradistinction to the 25 standards 14 described in connection with the preferred form of the invention, the toy disclosed in Fig. 4 embodies spaced parallel side walls 25 which rise from the opposite longitudinal edges of the base 26, and have 30 fitted therebetween the sounding block 26 carried by one end of the base. The toy disclosed in this figure is otherwise similar to the form shown in Fig. 3, and is operated in identically the same manner as the preferred 35 form of the invention.

While it is believed that from the foregoing description the nature and advantages of the invention will be readily apparent, I desire to have it understood that I do not 40 limit myself to the exact construction and arrangement of parts illustrated, and that such changes may be resorted to when desired as fall within the scope of the invention as claimed.

45 What is claimed is:—

1. A toy of the character described embodying a base, a sounding block arranged at one end of the base, spaced parallel members carried by the base, a shaft journaled

between said members, a finger actuated 50 clapper secured to said shaft, yieldable means normally maintaining said clapper longitudinally of the base with one end in contact with said sounding block, and the opposite end of said clapper projecting beyond the base and having an inclined finger engaging portion. 55

2. A toy of the character described embodying a base, a sounding block arranged at one end of the base, spaced parallel members carried by the base, a finger actuated clapper pivotally mounted between said members, a spring having one end associated with the base, and its opposite end connected with the clapper and normally maintaining the latter in a position longitudinally of the base with one end in contact with said sounding block. 60

3. A toy of the character described embodying a base, a sounding block arranged at one end of the base, spaced parallel members carried by the base, a shaft journaled between said members, a finger actuated clapper secured to the shaft, a leaf spring having a hook terminal embracing one edge 75 of the base, the opposite terminal of said spring being interposed between the shaft and clapper respectively, said spring maintaining said clapper normally in a position longitudinally of the base with one end contacting the sounding block, and the opposite end of said clapper projecting beyond the base for the purpose specified. 80

4. A toy of the character described embodying a base, a hollow metallic sounding 85 block arranged at one end of the base, said block being constructed from a single piece of material and of substantially U-shaped formation in cross section, a finger actuated clapper pivoted at a point between its ends, 90 and yieldable means for normally holding said clapper disposed longitudinally of the base with one end contacting said sounding block, and its opposite end projecting beyond the base. 95

In testimony whereof I affix my signature.

OSCAR H. GRAVELINE.
